United States Patent Office.

J. J. KENDALL, OF TROY'S STORE, NORTH CAROLINA.

Letters Patent No. 95,354, dated September 28, 1869.

IMPROVED WASHING-MACHINE.

The Schedule referred to in these Letters Patent and making part of the same.

To all whom it may concern:

Be it known that I, J. J. KENDALL, of Troy's Store, Randolph county, North Carolina, have invented a new and improved Washing-Machine; and I do hereby declare that the following is a full, clear, and exact description thereof, which will enable others skilled in the art to make and use the same, reference being had to the accompanying drawing, forming part of this specification.

The drawing represents a vertical longitudinal section of my improved washing-machine.

This invention relates to a new machine for washing clothes, in which, by means of a system of horizontally-operating plungers, and of vertically-movable slides, the requisite action is produced on the articles to be washed.

The invention consists chiefly in the construction of said plungers, as will be hereinafter fully described.

A, in the drawing, represents the suds-box, made of suitable size and shape, with a nearly horizontal bottom, *a*.

The bottom is, at one end, somewhat depressed, to form a shoulder, *b*, as shown.

B B are a series of sliding boxes or pressers, suspended, by means of arms *c c*, from a transverse shaft or bar, *d*, that is arranged on standards *e*, of the suds-box.

Each arm is, by a pitman, *f*, connected with a crank, *g*, of a crank-shaft, *C*, that has its bearings at one end of the suds-box.

By turning the crank-shaft, the pressers B will be swung on the bar *d*, and will, as the arms *c* are of considerable length, move almost in a horizontal plane.

The arms *c c* have projecting elbows *h*, at their upper ends.

To the same are pivoted the upper ends of rods *j j*, that carry at their lower end perforated plates D D, with roughened surfaces. The surfaces of the pressers B, opposite the plates D, are also perforated and roughened, as shown. There is one plate or slide D opposite to, and in connection with each press B.

As the press moves toward its slide, said slide is drawn up, and thereby rolls the clothes that are between B and D, while the same are being pressed.

The shoulder *b*, and a friction-roller, *i*, serve as guides for the slides D.

The water which rushes out from behind the slide, when the presser is withdrawn, throws the clothes somewhat away from the slide, to allow the same to move down without difficulty.

The friction-roller *i* serves, also, to stay the slides, while the clothes are pressed against them.

Having thus described my invention, What I claim as new, and desire to secure by Letters Patent, is—

The boxes or pressers B B, provided with the slats *i*, in combination with the perforated plates D D, as and for the purpose set forth.

The above specification of my invention signed by me, this 28th day of January, 1869.

J. J. KENDALL.
